UNITED STATES PATENT OFFICE.

WILLIAM F. SHEDD, OF RIPLEY, OHIO.

IMPROVEMENT IN PLOWS.

Specification forming part of Letters Patent No. **31,565**, dated February 26, 1861.

To all whom it may concern:

Be it known that I, WILLIAM F. SHEDD, of Ripley, in the county of Brown and State of Ohio, have invented a new and Improved Plow; and I do hereby declare that the following is a full, clear, and exact description of the same, reference being had to the accompanying drawings, forming a part of this specification, in which—

Figure 1 represents a sectional side elevation of my invention. Fig. 2 is a rear elevation of the same. Fig. 3 is a plan or top view of the same.

Similar letters of reference in the three figures indicate corresponding parts.

This invention relates to a peculiar arrangement of parts for the purpose of adjusting the clevis so as to regulate the depth of plowing or to give more or less land, as may be desired.

The beam A of my plow is of the ordinary form and construction. To this beam the handles B are fastened by a pivot, *a*, passing through their front ends and through the beam, and their rear ends are supported by a bolt, *b*, which passes through the center of the cross-bar *c*, that connects the two handles. By means of this bolt the handles can be adjusted higher or lower to suit persons of different stature. The lower end of the bolt *b* passes through the beam, and it serves to retain the rear end of the standard *c*, the upper portion of which divides into two arms, *d* *e*, as clearly shown in Fig. 1 in the drawings. The upper end of the arm *d* of the standard is rounded and provided with a screw-thread, and it passes up through the beam, being fastened to the same by means of a nut, *f*. This nut also serves to retain the front end of the brace *g*, which steadies the upper end of the bolt *b* and strengthens the position of the handles *B*. The front edge of the arm *d* of the standard is curved, and it may be sharpened to facilitate the passage of the plow through sod or hard ground intersected by roots, &c.

The share or shovel *D* is attached to the

lower end of the standard by means of a loop or staple, *h*, which is firmly riveted to the under side of the shovel, and which slips over the end of the standard, and it is retained by means of a wedge, *i*. A shoulder, *j*, on the standard, which catches over the upper edge of the shovel, assists materially in steadyng the same. By withdrawing the wedge *i* the shovel can be removed and replaced by another with little trouble.

The clevis *E* of my plow is secured to the beam by means of a bracket, *F*, which is attached to the front end of the beam by a pivot, *k*. The upper flange of the bracket *F* extends through the stirrup *G*, which is fastened to the beam by the bolt *l*, and the inner end of said flange is so arranged that it allows the bracket *F* to turn on the pivot *k* in a horizontal plane until one edge or the other of said flange strikes the stirrup *G* on one side or on the other. The position of the bracket *F* is regulated by a thumb-screw, *m*, which passes through a nut, *n*, and this nut is pivoted to the inner end of the upper flange of said bracket, so that by turning the screw said flange is moved from one side of the stirrup to the other. By these means the clevis is adjusted so as to give more or less land to the plow. The clevis itself is attached to the bracket *F* by means of a screw, *o*, which screws into the rear end of the clevis, so that by turning said screw the clevis is raised or lowered, as may be desired. By this arrangement the depth of plowing can be regulated with ease and facility.

Having thus fully described my invention, what I claim as new, and desire to secure by Letters Patent, is—

The arrangement of the pivoted bracket *F*, stirrup *G*, and regulating-screws *m* and *o*, to operate in combination with the clevis *E*, in the manner and for the purposes specified.

WM. F. SHEDD.
